UNITED STATES PATENT OFFICE.

WILLIAM LAMBERTI, OF NEW YORK, N. Y.

AUTOMATIC AUTOMOBILE FENDER.

1,408,362.

Specification of Letters Patent. Patented Feb. 23, 1922.

Application filed July 18, 1921. Serial No. 485,549.

To all whom it may concern:

Be it known that I, WILLIAM LAMBERTI, a citizen of the United States, residing at the city of New York, borough of Manhattan, county and State of New York, have invented a certain new and useful Automatic Automobile Fender, of which the following is a specification.

This invention is a fender adapted for use, more particularly, on motor driven vehicles such as automobiles, and the object in view is to afford means for saving the life and limbs of a pedestrian, or other person in the path of the vehicle, by the automatic action of a fender carried by said vehicle.

According to my invention, a curtain composed of strong flexible material is coiled in a compact condition and encased within a suitable housing for protection against the weather, dust, dirt, etc. With this curtain is associated actuating means in the form of a plurality of tubular members hung for pivotal movement with respect to a bumper, said tubular actuating means being adapted for encasing appropriate springs which, when released, operate to draw the curtain to an extended position intermediate the tubular members, whereby the curtain presents a barrier to the body of a person from passing under the wheels of the vehicle. Appropriate latching means are employed for retaining the tubular members in a raised position and for locking the springs in an extended condition while allowing the curtain to be wound upon its spindle, said latching means being controllable by a movement of the bumper. The impact of the bumper with a pedestrian, represses said bumper and actuates the latching means, whereupon the

tubular members and the spring devices are released simultaneously, as a result of which the tubular members drop to their operative positions and the tension of the springs is brought into service for unwinding the flexible curtain and drawing said curtain out of the housing to an extended operative position to fulfill the function of a barrier.

Other functions and advantages of the invention will appear from the following description taken in connection with the drawings, wherein—

Figure 1 is a side elevation, partly in section, of an automatic fender embodying my invention.

Figure 2 is a front elevation, with parts

in section, showing the barrier curtain extended.

Figure 3 is a detail view illustrating the latching means associated with the curtain and the pivotal tubular actuator members.

A designates a housing for a curtain B, the latter being composed of a strong flexible fabric or other material to stand the strains and stresses due to the impact of a person with the barrier afforded by said curtain. The housing is shown as a cylindrical casing closed at the ends and provided with a longitudinal slot a through which extends the curtain, as shown in Figure 3.

C is a winding spindle in the form of a spring actuated roller, the spring being indicated at c in Figure 2. This spindle is mounted for rotation within the housing, and on it is coiled the flexible material composing the curtain B.

With the curtain is associated an actuator in the form of a plurality of arms D D, the same being mounted for pivotal movement. As shown, each arm D is in the form of a tube, provided in one side thereof with a longitudinal slot d, and at one end with a wheel hanger e, the latter being fixedly secured to the tubular member D, said wheel hanger being provided with a roller shoe E' of any desired construction. At the other end, each arm is closed by a head f from which extends a shank piece f' adapted to be fitted loosely on the threaded rod f² projecting from the ends of the housing A, said arm being held from sliding movement on the rod f² by the nuts f³, whereby the tubular members D D are supported for pivotal movement with respect to the curtain winding means.

E is a cross member in the form of a rod provided with enlarged ends e', said rod being slidable in the slots d of the tubular members D D and said ends e' being fitted within the chambers of said tubular members for sliding movement to serve as guides for the cross member. To this cross member E is secured an edge portion of the flexible curtain B, and with said cross member co-operates an appropriate latching mechanism, the same being actuated by a bumper.

As shown in Figure 1, a bumper F is mounted in advance of the housing A, said bumper extending parallel to the housing and being movable relatively thereto. This bumper is equipped with depending arms G terminating in hooks g and constituting the

latches, one at each side of the curtain, see Figure 2. The latches are movable with the bumper so as to be actuated thereby, and said latches extend rearwardly and downwardly with respect to the bumper so as to engage with the cross member E for locking the latter at one end of the slots d when the curtain is coiled upon the winding spindle, whereby the latches co-operate with the tubular members D for retaining said members in the raised and inclined positions shown by full lines in Figure 1. The bumper F is mounted for movement by any suitable means; as shown, the bumper is slideable upon the guide rods g' attached to the housing, and said bumper is pressed forwardly to an active position by the energy of coiled springs F' which loosely encircle the guide rods. It is apparent that other means may be employed for supporting the bumper in movable relation to the housing.

H are coiled springs encased within the tubular members D. Each spring is attached at one end to the lower end of the tubular member or to the wheel hanger thereof as at h in Figure 1, whereas the other end of the spring is fastened to the guide e' of the curtain rod or cross member E.

30 The fender as an entirety is attached to, or mounted on, the motor driven vehicle in a suitable manner. The housing occupies a stationary position, with the members D of the actuator extending forwardly, and with 35 the bumper F extending crosswise between said tubular members. The curtain B is coiled on the spindle within the housing, thus drawing on the cross member E in order to distend the springs H, and the latches 40 G engaging with the cross member for retaining the tubular members D in the raised inclined positions and for retaining said springs H under tension. The impact of a person against the bumper F forces the latter rearwardly against the tension of springs F', the effect of which is to disengage latches G from the cross member E, whereupon the tubular members D and springs H are released at the same time, as a result of which 50 the tubular members D drop or fall for the roller shoes E' to rest upon the roadway and the springs H react in a manner to unwind the curtain from the spindle and to draw said curtain to the extended position shown 55 by full lines in Figure 2. During the unwinding of the curtain by the pull of springs H it slides freely in a slot i of a cross rod I extending between the tubular members D and attached fixedly thereto. The curtain is thus lowered and unwound automatically so as to be supported by and between the cross rods E' and I, and said curtain thus affords a barrier extending upwardly from the roadway, whereby said curtain presents a barrier effective in prevent-

ing the vehicle wheels from riding over the body or limbs of a person who may be knocked down by the movement of the vehicle.

Having thus fully described the invention, what I claim as new and desire to secure by Letters Patent is:

1. In a fender of the class described, a curtain composed of flexible material, means for winding said curtain, an actuator hung for movement relatively to the curtain-winding means, spring mechanism effective in drawing the curtain downwardly so as to extend in a continuous sheet from side to side of the fender, and latching means co-operating with said actuator and the spring mechanism for locking and releasing the same.

2. In a fender of the class described, a curtain composed of flexible material, means for winding said curtain, an actuator hung for movement relatively to the curtain-winding means, springs encased within the actuator and connected with the curtain for unwinding the latter concurrently with a pivotal movement of said actuator, a bumper, and latch mechanism operable by the bumper and co-operating with the actuator and the springs for releasing the same upon the re-pression of said bumper.

3. In a fender of the class described, a curtain composed of flexible material, winding means therefor, an actuator composed of a plurality of tubular members hung for movement relatively to the curtain winding means, a bumper, latching means actuated by the bumper and operating for retaining the tubular members in a raised inactive position, and springs encased within the tubular members and co-operating with the curtain for unwinding the latter upon releasing said tubular members from the restraint of said latching means.

4. In a fender of the class described, a curtain composed of flexible material, means for winding the same, a bumper, a plurality of tubular slotted members hung for pivotal movement, a cross member slideable in the slots of said tubular members and attached to the curtain, springs encased within the tubular members and attached to the cross member for unwinding the said curtain, and latching means controllable by the bumper and co-operating with the cross member for retaining the tubular members in a raised position and for placing said springs under tension.

5. In a fender of the class described, a curtain housing, a flexible curtain, means for winding said curtain in a compact condition within said housing, an actuator embodying a plurality of pivotal members, a bumper, latching means actuated by the bumper and co-operating with the actuator for retaining the latter in a raised position,

and spring mechanism connected with the curtain and co-operating with the latching means to be held thereby in a distended position.

- 5 6. In a fender of the class described, a curtain composed of flexible material, means for winding the same, a plurality of tubular members provided with shoes and hung for pivotal movement with respect to said winding means, latching means for retaining the tubular members in a raised position, and spring mechanism held in a distended condition by the action of said latching means, said spring mechanism being connected with
10 15 said curtain and adapted, when released by the latching means, to automatically unwind the curtain.

7. A fender of the class described embodying a fixed casing, a spring-actuated winding spindle therein, a curtain composed of 20 flexible material and adapted to be coiled on said spindle, a plurality of pivoted tubular arms each having a roller shoe, a cross member slidable relatively to said pivoted arms and attached to said curtain, bumper-controlled 25 latching means positioned for engagement with said cross member, springs encased within the tubular arms and attached to the cross member, and a fixed guide member through which the flexible 30 curtain is free to slide.

In testimony whereof I have hereto signed my name this 16th day of July, 1921.

WILLIAM LAMBERTI
